UNITED STATES PATENT OFFICE.

DAVID LARSON, OF YONKERS, NEW YORK.

ELECTRIC ELEVATOR.

No. 827,924.

Specification of Letters Patent.

Patented Aug. 7, 1906.

Application filed July 24, 1905. Serial No. 270,955.

To all whom it may concern:

Be it known that I, DAVID LARSON, a subject of the King of Sweden and Norway, and a resident of Yonkers, in the county of Westchester and State of New York, have invented certain new and useful Improvements in Electric Elevators, of which the following is a specification.

My invention relates to a controlling system for electric elevators, and is especially applicable to such electric elevators as are operated by alternating currents.

I will describe my invention in the following specification and point out the novel features thereof in claims.

Referring to the drawings, Figure 1 shows diagrammatically an electric elevator with certain connected parts and electrical circuits which I employ in carrying out my invention. Figs. 2, 3, 4, and 5 illustrate modifications of one part of the apparatus shown in Fig. 1. Fig. 6 is a side elevation, partly in section, of an electrically-actuated brake. Fig. 7 is a front elevation of a detail of a locking device, and Figs. 8 and 9 show in side elevation the parts shown in Fig. 7 in different positions.

Like characters of reference designate corresponding parts in all of the figures.

10 designates an elevator-car, which may be connected to a winding-drum 22 by means of a rope or cable 11. 12 is a counterweight which may be connected to this same winding-drum by another rope or cable 13.

20 designates an electric motor, which is arranged to operate the elevator-car. It is shown in the drawings as an alternating-current motor; but it may be any suitable type of motor.

21 is the motor-shaft, and this may be connected to the winding-drum 22 by suitable gearing within the casing 23.

30 is an electrically-actuated brake. It may be constructed as shown in Fig. 6, in which an electromagnet 31 is arranged with a solenoid coil or winding 32, within which is a loose core 33. The frame of magnet 31 and also the core 33 are preferably laminated when used with alternating currents. The magnet 31 is supported by a frame 34. Directly below the magnet a portion 34^A of this frame is finished to receive a weight or plunger 35. These parts are preferably arranged to fit closely, but to allow the plunger 35 to have a vertical movement within the portion 34^A. The magnet-core 33 rests upon but is

not attached to the plunger 35. A lever 36 is pivoted at 36^A to the frame 34 and is attached at 36^B and 36^C to the ends of a brake-band 37, which partially surrounds a brake-pulley 24, which is rigidly attached to the motor-shaft 21. The other end of the lever 36 is extended to a point directly under the plunger 35, and the latter rests upon it. A spring 38 may be placed under the lever 36 and arranged to partially overcome the action of the weight of the plunger 35 and the core 33. Before proceeding with the description of the rest of the apparatus I will describe the operation of this brake. When the magnet 31 is energized by having a current passed through its winding 32, it will lift its core 33. A projection 33^A may be provided on the upper end of the core 33 and a corresponding recess 31^A provided in the magnetic frame of magnet 31, if desired, in order to increase the length of pull of the magnet and to increase its efficiency. As the core is not attached to anything and the magnet has to lift only the weight of this core, the core itself may be designed to have considerable weight. Moreover, as the core when raised has a tendency to short-circuit some of the magnetic lines in the frame of the magnet 31, and as this has a choking effect upon the current in winding 32 the latter may be designed to carry a comparatively heavy impulse-current, which will immediately be automatically cut down as soon as it has done its work. This, then, is a particularly efficient arrangement. The spring 38 is made of sufficient strength to lift the plunger 35 and move its connected parts when the core 33 is raised from it. It will then push up the end of lever 36, and thereby loosen the brake-band 37. When the current is cut off from the winding 32 and the magnet thereby becomes deenergized, it allows the core 33 to drop down onto the plunger 35, and the combined weight of the core and the plunger is sufficient to overcome the action of spring 38 and to apply the brake. The portion 34^A of frame 34 which receives the upper portion of plunger 35 may be made a sufficiently close fit to act as a dash-pot and to retard the movement of plunger 35. When the core is raised, it is clear of the plunger 35—that is, it is arranged to be raised above the upper limit of the plunger's movement—so that no vibration of the core due to alternations of the exciting-current or other causes will be transmitted to the plunger and the brake.

Referring again to Fig. 1, 40 designates a suitable source of electrical supply. It is here shown as a source of alternating-current supply connected to the primary of a transformer 41. The secondary is connected through a main switch 42 by means of the mains 43, 44, and 45 to various parts of the apparatus. 50 designates a base, upon which is mounted an electrically-actuated reversing or starting switch for the motor 20. This switch comprises two electromagnets 51 and 52 and certain contacts and other parts, which I will now describe. 51^B and 51^C are stationary contacts situated near magnet 51. 51^D and 51^E are movable contacts arranged to be closed against the stationary contacts by means of a spring 51^F whenever magnet 51 is energized and lifts its core 51^A, but to be pushed down and away from the stationary contacts by the weight of core 51^A when the magnet is not energized. The main 43 is connected to stationary contact 51^C, and the main 45 is connected to stationary contact 51^B. One of the motor-terminals 26 is connected to movable contact 51^E by conductors 26^A and 26^B, and another of the motor-terminals 28 is connected to the other movable contact 51^D by conductors 28^A and 28^B. The main 44 is connected to the central motor-terminals 27. It is evident, then, that when magnet 51 is energized and allows the contacts which it controls to be closed the motor will receive current from the line and will rotate in one direction. Similarly when magnet 52 is energized and lifts its core 52^A a spring 52^F will close other contacts, which will cause the mains 43, 44, and 45 to be connected to the motor-terminals 28, 27, and 26, respectively, and will furnish current to the motor in the opposite direction and will cause it to rotate in the other direction.

I will now describe a novel arrangement for locking and interlocking the movable contacts of the reversing-switch. A three-armed lever 58 is pivoted at 53^A. One of its arms 53^B extends to a point beneath magnet 51. Another of its arms 53^C extends to a point beneath magnet 52, and its third arm 53^D extends to the lock 54. Extending below the springs 51^F and 52^F and connected to the parts which carry the movable contacts are projections 51^G and 52^G, which are adapted to engage with the arms 53^B and 53^C, respectively. When spring 51^F pushes movable contacts 51^D and 51^E up, the projection 51^G first strikes against the arm 53^B and prevents the contacts from reaching the stationary contacts above them unless the lock 54 is open and allows the arm 53^B to move with the movable contacts. If the lock 54 is open and allows such movement, it may be seen that the projection 51^G will hold the arm 53^B in a raised position and the arm 53^C in a lowered position, which will cause the projection 52^G to prevent the closing of the contacts

below magnet 52 as long as the contacts below magnet 51 remain closed. The lock itself comprises a sliding bar 54^A, which is provided with a slot 54^B and which is controlled by the movement of motor 20 through the agency of a speed-governor 55. This governor may be connected to the motor by means of a belt 55^A, which runs over a pulley 25 on the motor-shaft 21. A projection 53^E on the end of arm 53^E is arranged to pass through the slot 54^B when the motor is at rest and the parts are in the positions shown in Figs. 7 and 8, but to abut against and be locked by sliding bar 54^A when the motor is running and the latter is raised by the action of the governor 55 into the position shown in Fig. 9. The result of this locking arrangement is that it makes it impossible for one to reverse the current to the motor before the latter has been brought to rest.

I will now show how the reversing-switch may be operated electrically from a distance. A manually-operated circuit-closer 60 may be provided at a convenient place—for example, on the elevator-car 10, as shown. This circuit-closer or switch 60 comprises a pivoted switch-arm 61 and three stationary contact-segments 62, 63, and 64. The segment 62 is connected to main 44 by a conductor 44^A. The segment 63 is connected to one end of the winding of magnet 51 by a conductor 63^A, and the segment 64 is connected to one end of the winding of magnet 52 by a conductor 64^A. The other ends of these magnets are connected to the main 45 by a conductor 45^A. Now when the switch-arm is moved to the left a circuit is completed from main 44 through conductor 44^A, segment 62, switch-arm 61, segment 63, conductor 63^A, winding of magnet 51, and to the main 45 by conductor 45^A. This will cause magnet 51 to be energized and to lift its core 51^A, and thus to control the operations before pointed out. Similarly when the switch-arm is moved to the left a circuit will be completed from main 44, conductor 44^A, segment 62, switch-arm 61, segment 64, conductor 64^A, winding of magnet 52, and conductor 45^A to main 45. This will cause magnet 52 to be energized and to perform its functions.

I will now describe my novel arrangement for automatically controlling the acceleration of the motor 20. An opposition element 70 is connected in the motor-circuit. It may be resistance or inductance or any other desired arrangement for preventing the motor from receiving too much current. It is here shown as a star-connected resistance connected to the rotor of the motor by conductors 71, 72, and 73 through slip-rings of ordinary construction on the motor-shaft. When the motor is started, this resistance is included in the rotor-circuit, and the motor will then rotate slowly.

80, 81, and 82 designate a series of electro-

magnets similar in construction to magnets 51 and 52, before described. In this case, however, the magnets are arranged to be susceptible to a variable strength of current, so that as the current through their coils increases in strength they will be actuated one by one. This may be accomplished in a number of ways—as, for example, by making the cores of different weights or of different lengths or, as shown, by making their coils or windings of different number of turns. The winding of magnet 82 has the greatest number of turns. Consequently it will act first. The contacts which it controls in a manner similar to that already described are arranged to short-circuit a portion of the resistance 70. The winding of magnet 81 has the next largest number of turns, and as the current in the coils increases it will act next. The contacts which it controls are arranged to short-circuit another portion of resistance 70. In a similar manner magnet 80, the coil of which has the least number of turns, will act last, and the contacts which it controls will short-circuit the remainder of resistance 70. In this way the resistance 70 will be cut out from the motor-circuit in a number of steps and will allow the motor to take more current from the line and to speed up.

The above operation should be gradual and proportional to the speed of the motor, which of course will vary with different load conditions. This may be accomplished in a number of ways. I have shown several of these ways to illustrate this part of my invention.

In Fig. 1 the lower ends of the windings of magnets 80, 81, and 82 are connected to the main 44 by a conductor 44^B. Their upper ends are connected by a conductor 44^C to one end of a variable resistance 90. This resistance 90 is connected to a series of stationary contacts 91, over which a pivoted contact-arm 92 is arranged to be moved. This arm 92 is connected by a conductor 44^D to the conductor which runs between contacts 52^D and 51^D, so that when magnet 52 is energized and allows the contacts which it controls to be closed the upper ends of the windings 80, 81, and 82 will be connected through resistance 90 and the conductors just pointed out and contacts 52^D and 53^B to main 43, and when magnet 51 is energized they will be similarly connected through magnets 51^D and 51^B to main 45. Thus the magnets will receive from the mains through resistance 90. The pivoted contact-arm 92 may be mechanically connected to the sliding rod 54^A by means of a link 93. This sliding rod is connected, as has been shown, to the governor 55, which is belted to the motor-shaft and is arranged to be lifted an amount proportional to the speed of the motor. This in turn will cause the pivoted contact-arm 92 to be moved over the stationary contacts 91 and to gradually cut out the resistance 90 and to thereby vary the current in magnets 80, 81, and 82 as the motor accelerates. This will cause the resistance 70 to be cut out of the motor-circuit step by step and may readily be adjusted to perform this operation at the desired rate.

Fig. 2 shows a modification in which the pivoted contact-arm 92 is moved over a series of stationary contacts 91', to each of which a terminal of one of the magnets 80, 81, and 82 is connected. In this case as the arm 92 passes over the contacts it closes circuits to the magnets one by one. The rest of the operation is similar to that already described.

In the modification shown in Fig. 3 the pivoted contact-arm 92 is moved over stationary contacts 91', as before; but these contacts are connected to various points in the primary of a transformer 100, so as to include more or less of it in circuit with the supply, and the windings of magnets 80, 81, and 82 are connected across the secondary of transformer 100, which of course induces an increasing voltage as more of its primary is energized, and thus furnishes the desired variable current to the magnets.

In Fig. 4 a pivoted arm 92' is mechanically connected to the plunger 102 of a choking-coil 101, which performs the function of resistance 90 in the arrangement shown in Fig. 1.

Fig. 5 illustrates another form of inductive device or transformer, in which a movable core 102' is moved by pivoted arm 92' within primary and secondary coils 103 and 104 by altering the magnetic lines within said device, and thereby causes the induced voltage to be varied in the desired manner.

The current to the electrically-actuated brake which I have previously described may be supplied by connecting the leads 32^A and 32^B from its winding 32 to the terminals 26 and 27, as shown in Fig. 1, in which case the winding 32 will be connected across two of the mains whenever the circuit is closed to the motor.

The special type of magnets herein shown and described I claimed in another application for patent, Serial No. 265,883, filed June 19, 1905. The present application shows many novel features of motor-control system. I have illustrated the invention by showing it applied to an electric elevator, but it is evident that it is applicable to many analogous uses—in fact, to any system wherein it is desired to control the movements of an electric motor from a distance—for example, the motor or motors on an electric railway car or train or those used for operating mill-tables. The motor-accelerating device may be used in conjunction with many forms of motor-controlling devices, such as regulating-transformers and various types of switches, whereby many types of

4

motors may be controlled. As the operation of this arrangement depends upon the speed of the motor itself, it is evident that accelerating devices will be actuated in proportion to the acceleration of the motor itself, which of course will be proportioned to the speed of the motor.

What I claim is—

1. In combination with a motor, a reversing-switch therefor, electromagnets having cores free from said reversing-switch but arranged to control the same, and independent means for actuating the reversing-switch when one of the magnets is energized.
2. In combination with a motor, a reversing-switch therefor, a pair of magnets having cores free from said circuit-closer but arranged to open said circuit-closer when the magnets are not energized, and independent means for closing the reversing-switch when either of the magnets is energized.
3. In combination with a motor, a reversing-switch therefor comprising two sets of contacts, a pair of electromagnets, cores therefor free from said reversing-switch but arranged to control the same, and independent means for actuating the reversing-switch and closing either set of its contacts when the corresponding one of said magnets is energized.
4. In combination with a motor, a reversing-switch therefor comprising two sets of contacts, a pair of electromagnets, cores therefor free from said reversing-switch but arranged to control the same, independent means for actuating said reversing-switch and closing either set of its contacts when the corresponding one of said magnets is energized, and means for preventing the closing of either set of said contacts when the other set of contacts is closed.
5. In combination with a motor, a reversing-switch therefor comprising two sets of contacts, a pair of electromagnets, cores therefor free from said reversing-switch but arranged to control the same, independent means for actuating the reversing-switch and closing either set of its contacts when the corresponding one of said magnets is energized, and means for preventing the closing of one set of contacts while the motor is running.
6. In combination with a motor, a reversing-switch therefor comprising two sets of contacts, a pair of electromagnets, cores therefor free from said reversing-switch but arranged to control the same, independent means for actuating said reversing-switch and closing either set of its contacts when the corresponding one of said magnets is energized, means for preventing the closing of either set of said contacts when the other set of contacts is closed, and means for preventing the closing of one set of contacts while the motor is running.
7. In combination with a motor, a revers-

ing-switch therefor comprising two sets of contacts, a pair of electromagnets, cores therefor free from said reversing-switch but arranged to control the same, independent means for actuating the reversing-switch and closing either set of its contacts when the corresponding one of said magnets is energized, and a locking device for said reversing-switch actuated by the movement of the motor.

8. In combination with a motor, a reversing-switch therefor comprising two sets of contacts, a pair of electromagnets, cores therefor free from said reversing-switch but arranged to control the same, independent means for actuating the reversing-switch and closing either set of its contacts when the corresponding one of said magnets is energized, and a locking device for said reversing-switch actuated by the movement of the motor, arranged to prevent the closing of one set of contacts after the other set of contacts has been closed unless the motor is at rest.

9. In combination with a motor, a reversing-switch therefor comprising two sets of contacts and a pair of alternating-current magnets, cores for said magnets free from said reversing-switch, one of said cores arranged to control one set of contacts and the other arranged to control the other set of contacts, and independent means for actuating the reversing-switch and closing one set of contacts when one magnet is energized, and other means for actuating the reversing-switch and closing the other set of contacts when the other magnet is energized.

10. In combination with a motor, a reversing-switch therefor, electromagnets having cores free from said reversing-switch but arranged to control the same, independent means for actuating the reversing-switch when one of the magnets is energized, circuits for said magnets, and a manually-operated switch in said circuits.

11. A motor, a reversing-switch therefor, electromagnets having cores free from said reversing-switch but arranged to control the same, independent means for actuating the reversing-switch when one of the magnets is energized, combined with a brake, an electromagnet, and a free core therefor arranged to control said brake.

12. A motor, a reversing-switch therefor, electromagnets having cores free from said reversing-switch but arranged to control the same, independent means for actuating the reversing-switch when one of the magnets is energized, combined with a brake, an electromagnet, a free core therefor arranged to control said brake, circuits for the reversing-switch magnets, a manually-operated switch in said circuits, and means for supplying current to the brake when the motor-circuit is closed.

13. In combination with a motor, an op-

- position element in circuit therewith, an electroresponsive device for removing said opposition element from the motor-circuit, and mechanical means comprising a centrifugal speed-governor dependent upon the speed of the motor for varying the current in said electroresponsive device.
14. In combination with a motor, an opposition element in circuit therewith, a plurality of electromagnets arranged to control the opposition element, and mechanical means comprising a centrifugal speed-governor dependent upon the speed of the motor arranged to vary the current in said magnets.
15. In combination with a motor, an opposition element in circuit therewith, a plurality of magnets, contacts controlled by said magnets connected to and arranged to short-circuit said opposition element, and mechanical means comprising a centrifugal speed-governor dependent upon the speed of the motor arranged to vary the current in said magnets whereby the contacts which are controlled by the magnets will be actuated so that they short-circuit the opposition element step by step.
16. In combination with a motor, an opposition element in circuit therewith, a plurality of electromagnets, contacts controlled by said magnets connected to and arranged to short-circuit said opposition element, a speed-governor mechanically connected to the motor, circuits for said magnets, and means actuated by said governor and in said circuits, for varying the current in said magnets.
17. In combination with a motor, an opposition element in circuit therewith, a plurality of electromagnets comprising free cores, contacts controlled by said cores connected to and arranged to short-circuit said opposition element, a speed-governor mechanically connected to the motor, circuits for said magnets, and means actuated by said governor and in said circuits, for varying the current in said magnets in proportion to the speed of the motor.
18. In an elevator, a hoisting mechanism, a motor, a brake, an electromagnet having a free core, said core arranged to control the brake, an opposition element in the motor-circuit, an electroresponsive device for removing said opposition element from the motor-circuit, and mechanical means dependent upon the speed of the motor for varying the current in said electroresponsive device.
19. In an elevator, a hoisting mechanism, a motor, a brake, an electromagnet having a free core, said core arranged to control the brake, an opposition element in the motor-circuit, a plurality of electromagnets comprising free cores, contacts controlled by said cores connected to and arranged to short-circuit said opposition element, a speed-governor mechanically connected to the motor,
- circuits for said magnets, and means actuated by said governor and in said circuits, for varying the current in said magnets in proportion to the speed of the motor.
20. In an elevator, a car, a hoisting mechanism, a motor, a brake, an electromagnet having a free core, said core arranged to control the brake, an opposition element in the motor-circuit, a plurality of electromagnets comprising free cores, contacts controlled by said cores connected to and arranged to short-circuit said opposition element, a speed-governor mechanically connected to the motor, circuits for said magnets, means actuated by said governor and in said circuits, for varying the current in said magnets in proportion to the speed of the motor.
21. In combination with a motor, a reversing-switch therefor, electromagnets having cores free from said reversing-switch but arranged to control the reversing-switch, independent means for actuating the reversing-switch when one of the magnets is energized, an opposition element in circuit with the motor, an electroresponsive device for removing said opposition element from the motor-circuit, and mechanical means dependent upon the speed of the motor for varying the current in said electroresponsive device.
22. In combination with a motor, a reversing-switch therefor comprising two sets of contacts, a pair of electromagnets, cores therefor free from said reversing-switch but arranged to control the same, independent means for actuating the reversing-switch and closing either set of its contacts when the corresponding one of said magnets is energized, an opposition element in circuit with the motor, a plurality of electromagnets comprising free cores, contacts controlled by said cores connected to and arranged to short-circuit said opposition element, a speed-governor mechanically connected to the motor, circuits for said magnets, and means actuated by said governor and in said circuits, for varying the current in said magnets in proportion to the speed of the motor.
23. In an elevator, a car, a motor, a reversing-switch therefor comprising two sets of contacts, a pair of electromagnets, cores therefor free from said reversing-switch but arranged to control the same, independent means for actuating the reversing-switch and closing either set of its contacts when the corresponding one of said magnets is energized, an opposition element in circuit with the motor, a plurality of electromagnets comprising free cores, contacts controlled by said cores connected to and arranged to short-circuit said opposition element, a speed governor mechanically connected to the motor, means actuated by said governor and in said circuits, for varying the current in said magnets in proportion to the speed of the motor,

and a switch in the car arranged to control the movement of the motor.

24. In combination with a motor, a brake, an electromagnet having a free core, said core arranged to control said brake, a reversing-switch, electromagnets having cores free from said reversing-switch but arranged to control the reversing-switch, and independent means for actuating the reversing-switch when one of the latter magnets is energized, an opposition element in circuit with the motor, an electroresponsive device arranged to remove said opposition element from the motor-circuit, and mechanical means dependent upon the speed of the motor for varying the current in said electroresponsive device.

25. In combination with a motor, a brake, an electromagnet having a free core arranged to be lifted when the magnet is energized, means for releasing the brake when the core is lifted, means dependent upon the weight of the core for applying the brake, a reversing-switch comprising two sets of contacts, a pair of electromagnets, cores therefor free from said reversing-switch but arranged to control the same, independent means for actuating the reversing-switch and closing either set of its contacts when the corresponding one of said magnets is energized, an opposition element in circuit with the motor, a plurality of electromagnets comprising free cores, contacts controlled by said cores connected to and arranged to short-circuit said opposition element, a speed-governor mechanically connected to the motor, circuits for said magnets, and means actuated by said governor and in said circuits for varying the current in said magnets in proportion to the speed of the motor.

40 26. In combination with a motor, a brake, an electromagnet having a free core arranged to be lifted when the magnet is energized, means for releasing the brake when the core is lifted, means dependent upon the weight of the core for applying the brake, a reversing-switch comprising two sets of contacts, a pair of electromagnets, cores therefor free from said reversing-switch but arranged to control the same, independent means for actuating the reversing-switch and closing either set of its contacts when the corresponding one of said magnets is energized, an opposition element in circuit with the motor, a plurality of electromagnets comprising free cores, contacts controlled by said cores connected to and arranged to short-circuit said opposition element, a speed-governor mechanically connected to the motor, circuits for said magnets, means actuated by said

60 governor and in said circuits for varying the current in said magnets in proportion to the speed of the motor, and a manually-operated circuit closer.

27. In an elevator, a car, a hoisting mechanism, a motor, a brake, an electromagnet

having a free core arranged to be lifted when the magnet is energized, means for releasing the brake when the core is lifted, means dependent upon the weight of the core for applying the brake, a reversing-switch comprising two sets of contacts, a pair of electromagnets, cores therefor free from said reversing-switch but arranged to control the same, independent means for actuating the reversing-switch and closing either set of its contacts when the corresponding one of said magnets is energized, an opposition element in circuit with the motor, a plurality of electromagnets comprising free cores, contacts controlled by said cores connected to and arranged to short-circuit said opposition element, a speed-governor mechanically connected to the motor, circuits for said magnets, means actuated by said governor and in said circuits for varying the current in said magnets in proportion to the speed of the motor, and a manually-operated circuit closer in the car whereby the movements of the motor and the car may be controlled.

28. A motor, a governor connected to run with the motor, reversing means thereof and means controlled by the governor for preventing the reversing of the motor before the motor has come to rest.

29. A motor, a reversing-switch comprising two parts, and a governor connected to run with the motor and arranged to permit but one of the two parts of the reversing-switch to be actuated at once.

30. An alternating-current motor, an opposition element in circuit therewith, an electroresponsive device for controlling said opposition element, circuits for the electroresponsive device, and inductive means in said circuits controlled by the speed of the motor and arranged to vary the current in the electroresponsive device.

31. An alternating-current motor, an opposition element in circuit therewith, an electroresponsive device for controlling said opposition element, a speed-governor mechanically connected to the motor, a circuit for the electroresponsive device, and inductive means in said circuit controlled by said governor and arranged to vary the current in said circuit.

32. In combination with a motor, a source of alternating-current supply, a reversing-switch for the motor, alternating-current magnets having cores disconnected from said reversing-switch but arranged to control the same, and independent means for actuating the reversing-switch when one of the magnets is energized.

33. A source of alternating-current supply, a motor, a reversing-switch therefor, electromagnets having cores disconnected from said reversing-switch but arranged to control the same, independent means for actuating the reversing-switch when one of the

magnets is energized, combined with a brake, an alternating-current magnet, and a free core therefor arranged to control said brake.

5 34. In combination with an alternating-current motor, an opposition element in circuit therewith, a plurality of electromagnets, contacts controlled by said magnets connected to and arranged to short-circuit said 10 opposition element, a speed-governor mechanically connected to the motor, single-phase circuits for said magnets, and means actuated by said governor and in said circuits, for varying the current in said magnets.

15 35. In an elevator, a car, a hoisting mechanism, an alternating-current motor, a brake, an alternating-current magnet having a free core, said core arranged to control the brake, an opposition element in the motor-circuit, a plurality of electromagnets comprising free cores, contacts controlled by said cores connected to and arranged to short-circuit said opposition element, a speed-governor mechanically connected to the motor, single-phase circuits for said magnets, means actuated by said governor and in said circuits, for varying the current in said magnets in proportion to the speed 25 of the motor, and a manually-operated switch in the car.

30 36. In an elevator, a source of alternating-current supply, a car, an alternating-current motor, a reversing-switch therefor comprising two sets of contacts, a pair of alternating-current magnets, cores therefor disconnected from said reversing-switch but arranged to control the same, independent means for actuating the reversing-switch and closing 35 either set of its contacts when the corresponding one of said magnets is energized, an opposition element in circuit with the motor, a plurality of electromagnets comprising free cores, contacts controlled by said cores connected to and arranged to short-circuit said opposition element, alternating current-circuits for said magnets, a speed-governor mechanically connected to the motor, means actuated by said governor and in said circuits, 40 for varying the current in said magnets in proportion to the speed of the motor, and a switch in the car arranged to control the movement of the motor.

37. In an elevator, a source of alternating-current supply, a hoisting mechanism, an alternating-current motor, a brake, an alternating-current magnet having a free core arranged to be lifted when the magnet is energized, means for releasing the brake when the 45 core is lifted, means dependent upon the weight of the core for applying the brake, a reversing-switch comprising two sets of contacts, a pair of alternating-current magnets, cores therefor free from said reversing-switch but arranged to control the same, independent

means for actuating the reversing-switch and closing either set of its contacts when the corresponding one of said magnets is energized, an opposition element in circuit with the motor, a plurality of electromagnets comprising 70 free cores, contacts controlled by said cores connected to and arranged to short-circuit said opposition element, a speed-governor mechanically connected to the motor, alternating-current circuits for said magnets, means actuated by said governor and in said circuits for varying the current in said magnets in proportion to the speed of the motor, and a manually-operated circuit-closer in the car whereby the movements of the motor and 80 the car may be controlled.

38. In combination with a motor, an opposition element in circuit therewith, an electro-responsive device for removing said opposition element from the motor-circuit, and a 85 centrifugal speed-governor connected to the motor and arranged to control the current in said electroresponsive device.

39. In combination with a motor, an opposition element in circuit therewith, a plurality 90 of electromagnets arranged to control the opposition element, and a centrifugal governor connected to the motor and arranged to control the operation of said magnets.

40. In combination with a motor, an opposition element in circuit therewith, an electro-responsive device arranged to short-circuit said opposition element, a centrifugal speed-governor mechanically connected to the motor, circuits for the electroresponsive device, 100 and means actuated by said governor and in said circuits, for controlling the current in said electroresponsive device in proportion to the speed of the motor.

41. In combination with a motor, an opposition element in circuit therewith, a plurality 105 of electromagnets comprising free cores, contacts controlled by said cores connected to and arranged to short-circuit said opposition element, a speed-governor mechanically connected to the motor, circuits for said magnets, means actuated by said governor and in said circuits, for controlling the current in said magnets in proportion to the speed of the motor.

42. In an electric controller, the combination of a plurality of electromagnets, circuits for the magnets, and a centrifugal speed-governor arranged to control the magnet-circuits.

43. In an alternating-current controller, the combination of a plurality of magnets having disconnected cores, circuits for the magnets, and a centrifugal speed-governor arranged to control the magnet-circuits.

44. In an alternating controller, the combination of a plurality of magnets, single-phase circuits for the magnets, and a centrifugal speed-governor arranged to control the magnet-circuits.

45. In an alternating-current controller, the combination of a plurality of magnets having free cores single-phase circuits for the magnets, an inductive device in said circuits and a speed-governor arranged to control said inductive device. 60
46. An electric motor, a circuit therefor, an opposition element in the motor-circuit, an electroresponsive device arranged to control said opposition element, circuits for the electroresponsive device, and inductive means in said circuits arranged to control the current in the electroresponsive device in proportion to the speed of the motor. 65
47. An alternating-current motor, a circuit therefor, an opposition element in the motor-circuit, an electroresponsive device arranged to control said opposition element, circuits for the electroresponsive device and inductive means in said circuits arranged to control the current in the electroresponsive device in proportion to the speed of the motor. 70
48. An alternating-current motor, a circuit therefor, an opposition element in the motor-circuit, an electroresponsive device arranged to control said opposition element, circuits for the electroresponsive device and inductive means in said circuits arranged to 75 vary the current in the electroresponsive device in proportion to the speed of the motor. 75
49. An alternating-current motor, a circuit therefor, an opposition element in the motor-circuit, an electroresponsive device arranged to control said opposition element, a winding for the electroresponsive device and inductive means arranged to control the current in the electroresponsive device in proportion to the speed of the motor. 90
50. In an elevator, a hoisting mechanism, a motor, a brake, an electromagnetic actuator for controlling the brake, intermediate mechanism between the brake and the actuator, said actuator comprising a field of laminated magnetic material, a winding and an armature of laminated magnetic material disconnected from the brake mechanism, circuits for the brake-winding, a source of single-phase current-supply and means for 95 controlling the current in said circuit. 100
51. In an elevator, a hoisting mechanism, a motor, a brake, an electromagnetic actuator for controlling the brake, said actuator having a field and an armature of laminated magnetic material and a winding, a weight connected to said armature, a cylinder about said weight, said cylinder and weight forming a retarding device for the armature, circuits for the winding, a source of single-phase current-supply and means for controlling the current in said circuit. 105
52. In an elevator, a hoisting mechanism, a motor, a brake, an electromagnet and a disconnected core therefor arranged to control the brake. 110
53. In an elevator, a hoisting mechanism, a motor, a brake, an electromagnet having a disconnected core arranged to be lifted when the magnet is energized and means for releasing the brake when the core is lifted. 115
54. In an elevator, a hoisting mechanism, a motor, a brake, an electromagnet having a disconnected core arranged to be lifted when the magnet is energized, a spring for releasing the brake when the core is lifted and means dependent upon the weight of the core for applying the brake. 120
55. In an elevator, a hoisting mechanism, a motor, a brake, a magnet, a single-phase circuit for said magnet, a disconnected core 80 in said magnet arranged to be lifted when the magnet is energized and means for releasing the brake when the core is lifted. 125
56. An alternating current-motor, a circuit therefor, an opposition element in the motor-circuit, an electroresponsive device arranged to control said opposition element, and inductive means arranged to control the electroresponsive device in proportion to the speed of the motor. 130
57. An alternating-current motor, a circuit therefor, an opposition element in the motor-circuit, an electroresponsive device arranged to control said opposition element, inductive means arranged to control the electroresponsive device in proportion to the speed of the motor and a winding for the inductive means. 135
58. An alternating-current motor, a circuit therefor, an opposition element in the motor-circuit, an electroresponsive device arranged to control said opposition element, inductive means arranged to control the electroresponsive device in proportion to the speed of the motor, a circuit for said inductive means and a source of current-supply for the circuit of the inductive means. 140

In testimony whereof I have signed my name to this specification in the presence of two subscribing witnesses.

DAVID LARSON.
